United States Patent Office

Des. 176,117
Patented Nov. 22, 1955

176,117

PANCAKE GRIDDLE

Theodore L. Hanson, Kansas City, Mo., assignor to The Vendo Company, Kansas City, Mo., a corporation of Missouri

Application March 7, 1955, Serial No. 34,908

Term of patent 7 years

(Cl. D81—10)

Fig. 1.

Fig. 2.

Fig. 3.

Fig. 1 is a perspective view of the pancake griddle, showing my new design;

Fig. 2 is an end elevational view of the end of the pancake griddle opposite to that shown in Fig. 1; and

Fig. 3 is a top plan view of the pancake griddle.

I claim:

The ornamental design for a pancake griddle, as shown.
